UTILITY RACK

Filed July 28, 1928

INVENTOR:

SOPHIA M. SCHULZE

BY *Bruce S. Elliott*
ATTORNEY.

UNITED STATES PATENT OFFICE.

SOPHIA M. SCHULZE, OF ST. LOUIS, MISSOURI.

UTILITY RACK.

Application filed July 23, 1928. Serial No. 296,029.

The general object of my invention is to provide a utility rack designed, principally, to be hung upon the wall of a kitchen to hold containers of spices, condiments and extracts, 5 and which shall be characterized by extreme simplicity of construction and ready adaptation for its intended use.

The invention is illustrated in the accompanying drawing, in which—

10 Figure 1 is a perspective view of a utility rack constructed according to my invention;

Figure 2 is a sectional view on the line 2—2 of Fig. 1; and

15 Figure 3 is a cross-sectional view on the line 3—3 of Fig. 1.

In the preferred embodiment of my invention, as shown in the drawing, the rack, as to all but its back wall, is made of wire which is bent to form a top cross-wire 1, vertical 20 side wires 2, and rectangular end members 3. If desired, the parts of the rack just described may be made from a single length of wire, the free ends of the upper bars of the end members 3 being secured to the vertical side wires 2, as shown in Fig. 1, and said wire, moreover, being bent or coiled upon itself to form eyelets 4 at either end of the top wire 1 by means of which the rack may be supported by nails or the like on the wall. The end 25 members 3 have front vertical strand members 5 which are connected by cross-wires 6, one of which is located about centrally of the strands 5, and bottom strand members 7 which are connected by two wires 8 which form the bottom of the rack or container. The back 30 of the rack is formed by a strip 9 of tin or other suitable metal, which is secured at its ends about the vertical wires 2, as shown at 10 in Fig. 2.

40 From the above, it will be seen that the ends 3, front 6, bottom 8 and back 9 of the rack serve to provide a container or receptacle in which may be placed the spice boxes and bottles of extracts and any other containers 45 of substances used in the kitchen. The device, as a whole, being elongated in shape and of substantially open construction as to its front, makes access to the containers of spices, extracts, and the like, very easy and at the 50 same time, these articles are securely held and retained within the rack. It will be noted

that the retaining wires 6 at the front of the rack are so arranged as to leave the front of the rack practically open, and that they offer substantially no obstruction to the view 55 of the labels on the containers.

While I have shown, as stated, the preferred embodiment of my invention, it will be obvious to those skilled in the art that changes could be made in the device as illustrated without departing from the spirit of the invention. I do not wish, therefore, to be limited to the precise details of construction shown except as may be specified in the claims.

65 I claim:

1. A utility rack comprising a wire bent to form a top cross-wire, vertical side wires, and rectangular end members, a wire connecting the fronts of said end members, bottom 70 wires connecting the bottoms of said end members, and a back comprising a strip of metal of substantially the height of said end members and extending at opposite ends to said vertical side wires. 75

2. A utility rack comprising a wire bent to form a top cross-wire, vertical side wires, and rectangular end members and coiled upon itself to form eyelets at the ends of said top cross-wire, a wire connecting the fronts of 80 said end members, bottom wires connecting the bottoms of said end members, and a back comprising a strip of metal of substantially the height of said end members and extending between and secured at opposite ends to 85 said vertical side wires.

3. A utility rack comprising a wire bent to form a top cross-wire, vertical side wires, and rectangular end members, a longitudinal wire connecting the fronts of said end members and located below the plane of the upper sides thereof, parallel wires connecting the bottoms of said end members to provide a bottom for the device, and a back comprising a strip of metal of substantially the 90 height of said end members and extending between and secured at opposite ends to said vertical side wires.

In testimony whereof, I have hereunto set my hand.

SOPHIA M. SCHULZE.
